UNITED STATES PATENT OFFICE.

JOSEPH A. ANKER, OF LOS ANGELES, CALIFORNIA.

METALLURGICAL FURNACE.

SPECIFICATION forming part of Letters Patent No. 631,414, dated August 22, 1899.

Application filed June 10, 1897. Serial No. 640,223. (No model.)

To all whom it may concern:

Be it known that I, JOSEPH A. ANKER, a citizen of the United States, residing at the city of Los Angeles, in the county of Los Angeles, in the State of California, have invented 5 a new and useful Metallurgical Furnace, of which the following is a specification.

My invention relates to metallurgical furnaces for the reduction of ores; and it consists 10 in the construction and arrangement of parts whereby economy and convenience of operation are secured.

The objects of my invention are, first, to secure ease in handling the ore in smelting; 15 second, to facilitate making repairs and saving time in so doing, and, third, to save fuel in operating the furnace. I attain these objects by the mechanism illustrated in the accompanying drawings, in which—

20 Figure 1 is a vertical section of the furnace on the line 2 2 of Fig. 3. Fig. 2 is a side view of the front end of the furnace. Fig. 3 is a cross-section of the furnace on the line 3 3 of Fig. 1. Fig. 4 is a side view of the movable 25 hearth-section or smelting-pot.

Similar letters refer to similar parts throughout the several views.

A is the outer casing of the furnace; A', the chimney-stack; B, projections on the inner 30 side of the casing; C, the burners; C', openings for the burners C; D, the door in the stack end of the casing; D', a small door, and D'' a large door, in the front end of the furnace; d, a small door, and d' a large door, in 35 one side of the front end of the furnace; E, the movable hearth-section; e, the lining of the hearth-section; F, the discharge-port of the hearth-section; f, the ore in the hearth-section; G, the combustion-chamber in the 40 furnace above the crucibles.

The casing A and stack A' are constructed of suitable material and dimensions, depending 45 on the capacity of the furnace. The projections B B are so formed that their inner edges are even with the inner edges of the hearth-sections E. These hearth-sections are mounted on wheels and run on a track extending longitudinally through the furnace. This track is preferably on a grade, so that 50 the hearth-section can be easily moved to the front of the furnace. I have shown hydro-carbon-burners, in which crude petroleum is

used, but any other suitable burner and fuel to produce a blast may be used. I have also shown a furnace having five (5) movable 55 hearth-sections, but any suitable number may be used.

The operation of my furnace is as follows: Movable hearth-sections in sufficient number to fill the track in the furnace, loaded with a 60 suitable quantity of prepared ore, (and flux when needed,) are run into the furnace and the doors closed. The blast-flame is then projected against the ore in the first hearth-section until it is reduced to a molten state. 65 During the process of smelting the ore can be examined and its condition ascertained by opening the small side door d' or front door D''. Should more flux or ore be needed, it can be supplied through either of these doors. 70 When the ore in the first hearth-section is sufficiently smelted, the side door d may be opened and through the discharge-port F the metallic portion can be drawn off into a suitable receptacle. After this the slag is drawn 75 off, or the door D can be opened, the hearth-section run out to a suitable place, and the contents drawn off. As soon as the hearth-section in the front end is run out it is replaced by the one next to it, when its contents are then subjected to the action of the 80 blast. The door D is then opened, and another crucible loaded with ore is then run into the furnace and the door closed. This is repeated as often as desired, thereby making 85 the operation of my furnace continuous.

It will be observed that the ends of the hearth-sections fit closely together and the sides fit close to and about the projections B B, and the combustion-chamber G is thereby 90 formed, giving the necessary draft. It will also be observed that the heat not consumed by the first hearth-section passes along the chamber G and a large portion of it will be taken up by the ore in the other crucibles, as 95 the ore has a great affinity for heat, and that by the time the ore in the first hearth-section is thoroughly smelted that in the one next to it is quite highly heated. Another advantage of my furnace is that when the ore is 100 smelted the hearth-section is withdrawn and then can be repaired easily without shutting down the furnace.

I have shown two burners throwing the

flame into the front end of the first hearth-section and one burner on each side near the middle and directed slightly toward the rear; but I do not desire to limit myself to any particular number or to any particular direction or place of discharge of the burners, as it is obvious that the number and position largely depends on the capacity of the furnace.

10 Having thus described my furnace, what I claim as my invention, and desire to secure by Letters Patent, is—

15 1. A metallurgical furnace comprising a longitudinal combustion - chamber having openings at either end, one for the passage in of movable crucibles and one for the passage out of crucibles and a series of movable crucibles arranged to move longitudinally through the furnace, forming by their contact with each other the hearth of the furnace, and having in the front end thereof blast-flame burners arranged to shoot the flame down into the crucible in the front of the furnace and force the flames thereafter to pass 25 over the other crucibles, substantially as and for the purposes shown and described.

2. A metallurgical furnace the bottom of which is composed of a series of movable crucibles mounted on wheels, and adapted to be 30 run out of the furnace when desired, placed in close contact with each other in the furnace and forming thereby the bottom of the furnace; said furnace having blast - flame burners piercing the casing in the front thereof and arranged to shoot a flame first down 35 and into the end crucible, thence passing over the other crucibles and warming the ore in them preparatory to being subjected to the

blast-flame, substantially as and for the purposes described.

40

3. In a metallurgical furnace the combination of the series of movable hearth-sections E forming the bottom of the combustion-chamber, each having a discharge-port F and adapted to move longitudinally through the 45 furnace, casing A having side projections B B adapted to project over the side edges of the hearth-sections E, door D in the rear end of the furnace, adapted to be opened to permit of the passage into the furnace of the 50 hearth-section E, door D' in the front end of the casing, adapted to be opened to permit of the passage out of the furnace of the hearth-section E, door D'' in front end of the casing and door d' in the side of the front end of the 55 casing both adapted to be opened to inspect the ore in the hearth-section, and to permit the passage therethrough of more ore or flux into the hearth-section if needed; door d in the side of and in the front end of the casing 60 adapted to be opened to permit of the drawing off of the contents of the hearth-section, before the same is removed from the furnace, openings C' in the front end and in the sides of the front end of the casing above the hearth-section, adapted to permit the passage therethrough of the burners C, stack A' at the rear 65 end of the furnace, with burners C adapted to pass through the openings C' and discharge a blast-flame into the ore in the hearth-section 70 in the front end of the furnace substantially as set forth.

JOSEPH A. ANKER.
